SPRAYER WITH AGITATOR

Henry E. Brandt, North St. Paul, Minn.

Application May 21, 1938, Serial No. 209,302

5 Claims. (Cl. 299—97)

This invention relates to a spraying device and while the features of the invention might be applied to sprayers of different types, the invention is illustrated in a sprayer known as the knapsack type. Such a sprayer comprises a container adapted to be carried on the back of the operator and supported by straps so that the hands of the operator are free for operating said sprayer.

It is an object of this invention to provide such a sprayer having an agitating means for the liquid of simple and efficient construction.

It is a further object of the invention to provide a sprayer of the knapsack type having a container of greater width than thickness and an agitating means for the liquid comprising spaced oscillatable blades mounted in said container.

It is another object of the invention to provide a sprayer having a simple and efficient construction of screening means for the liquid to be sprayed.

It is also an object of the invention to provide a sprayer comprising a container of elongated form in horizontal cross section having a hinge cover at its top and a novel handle means for said cover.

It is still another object of the invention to provide a sprayer comprising a container adapted to be carried on the back of the operator having a plate secured to its rear side and spaced from said rear side, said plate having depressions therein for accommodating portions of the operator's body.

These and other objects and advantages of the invention will be fully set forth in the following description made in connection with the accompanying drawings in which like reference characters refer to similar parts throughout the several views and in which:

Fig. 1 is a view in front elevation of the device; Fig. 2 is a horizontal section taken substantially on line 2—2 of Fig. 3 as indicated by the arrow;

Fig. 3 is a vertical section taken substantially on line 3—3 of Fig. 6 as indicated by the arrows;

Fig. 4 is a view in side elevation of the device as seen from the right of Fig. 1;

Fig. 5 is a perspective view of portions of the agitator mechanism, said portions being shown in disassembled position;

Fig. 6 is a vertical section taken substantially on line 6—6 of Fig. 3 as indicated by the arrows;

Fig. 7 is a bottom plan view of the device;

Fig. 8 is a view in elevation showing a modification; and

Fig. 9 is a horizontal section on line 9—9 of Fig. 8.

Referring to the drawings a sprayer device is shown comprising a container 10. While this container might take various forms, in the embodiment of the invention illustrated it is shown as of elongated substantially elliptical form in horizontal cross section having a rear side 10a of convex form curved about a vertical axis and a front side 10b which has a concave surface curved about a vertical axis. The ends of said container are shown as curved so that in cross section the 10 container might be said to be of bean or kidney shape. It is thus seen that the container is of greater width than thickness. A bottom member 11 extends across said container having an upturned flange 11a secured to the walls thereof in 15 any suitable manner as by welding or soldering. A casing 12 shown as of cylindrical form is secured at its bottom to the bottom 11 substantially centrally thereof, casing 12 having a closed top and a chamber therein forming a liquid pressure 20 chamber. A small upstanding casing 13 is disposed at the bottom of casing 12 having an aperture 13a in its top adapted at times to be closed by a ball valve member 14 normally resting on a valve plug 15 secured in casing 13 and having an aperture therethrough normally closed by the ball 14 which rests on member 15. The bottom member 16 of casing 12 extends beyond said casing and downwardly, the same having a flange 16a secured to a flange 11a of a member 11. 25 Flanges 16a and 17a are secured together by a plurality of headed screws 19, the outer edge of a diaphragm 20 being disposed and secured between said flanges. Said diaphragm will be made of any suitable flexible material and a 30 chamber is thus formed beneath the bottom member 16 and above said diaphragm. An inlet means is provided comprising an apertured plate 21 on which rests a ball valve 22 normally closing the aperture therein. A plug 23 is secured in 35 bottom member 11 above plate 21 having an aperture disposed centrally therein and extending therethrough adapted to be closed at times by ball member 22. An operating means is provided for diaphragm 20 comprising a member 24 having a reduced upwardly extending central portion extending through a plate member 25 of inverted cup formation having a curved portion engaging the lower side of said diaphragm. A washer 27 engages the upper side of said diaphragm and is held in place by a nut 28 threaded onto the reduced portion of member 24. Member 24 has a cylindrical recess in its lower end, the upper closed portion of which is semi-spherical and in which is disposed a ball 29 carried on a 40

rod 30 having a reduced threaded portion extending through a tubular shaft 31 and held therein by a nut 32 on said threaded portion. A plug 33 is disposed in the bottom of member 24 being held therein by a pin 35 and having a semi-spherical top engaging ball 29. Stem 30 projects through a slot in one side of member 24. Shaft 31 is journalled in plates 36 adjacent the sides of container 10 and secured to said container, and projects through the end walls of said container as shown in Figs. 1, 6 and 7. Split keys 37 extend through shaft 31 adjacent the inner sides of plates 36 and prevent longitudinal movement of said shaft. Shaft 31 has tapped holes 31a extending therethrough adjacent its ends at the outer side of container 10 and said shaft extends through and is journalled in plates 46 secured to member 17 by the rivets 46a. A handle member 38 has a cylindrical portion having reduced threaded ends adapted to be screwed into apertures 31a and the same has an enlarged grip portion 38a shown as of cylindrical form. Tubes 39 connect with casing 12 adjacent its bottom and extend downwardly through bottom member 11 being sealed therein, and connect with bosses 40 at opposite sides of container 10 to which are connected coupling members 41. A discharge conduit or hose 42 has a coupling member 43 at its end adapted to be connected with either of members 41 and connected at its other end to suitable discharge pipe and nozzle (not shown). Plug 23 extends upwardly a short distance beyond bottom 11 and a cylindrical screen 44 of comparatively small diameter surrounds the top of said plug and upstands in container 10 alongside of casing 12. A resilient member 45 of strip form is secured to the side of casing 12 and extends therefrom substantially at right angles, the same having a depressed portion 45a adapted to fit in the top of screen 44 and having an outwardly projecting portion 45b forming a finger hold. Member 45 can be sprung upwardly by taking hold of portion 45b so that screen member 44 thus may be easily removed for cleaning or any other purpose.

46. An agitating means for the liquid in container 10 is provided, the same comprising a shaft 47 which extends across container 10 throughout the long dimension thereof, the same having one end journalled in a small bracket 48 secured to the inner side of the end wall of container 10. Shaft 47 has a central substantially U-shaped portion 47a formed therein extending about one side of casing 12 and at each side of said casing said shaft has plates 49 secured thereto, said plates extending about said shaft at the top thereof and having depending and diverging portions below said shaft. Plates 49 are secured to shaft 47 by pins 50. Shaft 47 at its other end has secured thereto by rivets 52 a sleeve 51. A rod 53 extends into the end of sleeve 51 and is removably secured therein by a split key 54 extending through slots in said sleeve and through a slot 53a in rod 53. Rod 53 extends outwardly through a member 55 having a portion extending through an aperture in the end wall of casing 10 with which sleeve 51 engages. Member 55 has a flange at the outer side of said end wall secured tightly thereagainst by soldering or welding. Member 55 has an outwardly projecting threaded portion adapted to receive a threaded gland member 56 having a chamber therein adapted to receive packing 57 surrounding rod 53. Rod 53 is bent substantially at a right angle at the outer side of member 55 and is again bent substantially at a right angle at its terminal por-

tion, which portion receives the eyelet formed at the upper end of a link member 58, said link member being held on said portion by a split key 59. Link 58 is connected at its other and lower end to a rod 60 having a reduced threaded portion extending through shaft 31 at one of the apertures 31a and container 10. Rod 60 is bent substantially at a right angle at its outer end to receive the eyelet at the lower end of link 58, said link being held thereon by the split key 61. The bent portion of rod 53 forms a crank arm oscillated by link 58 by the second crank arm formed by rod 60.

A plate 63 is secured to the front side of casing 10, said plate extending across said front side 16 and being secured to casing 10 in any suitable manner as by welding or riveting. Plate 63 is spaced from said front side of casing 10 for practically all of its width. A channel member 64 is disposed between plate 63 and said front side of 20 said container adjacent the top thereof. Depressions 63a having concave outer surfaces are formed at each side of plate 63 at the top thereof, said depressions being substantially semi-oval in elevation and having their greatest width and 25 depth at the top of said plate. A larger depression 63b is formed in plate 63 substantially centrally thereof, the same having a concave outer surface and also being substantially semi-oval in elevation and having its greatest width and depth 30 at the bottom side of said plate. Small brackets 65 are secured to plate 63 at opposite sides of depressions 63b and the central portions of which are journalled clips 66 shown as of substantially triangular form adapted to be engaged by snap 35 hooks 67 secured to the ends of straps 68 by which the device is supported on the shoulders of the operator. A bottom plate 70 is provided for the open lower end of the casing of container 10, the same being shown as somewhat waved or corrugated in cross section and as having a flange 70a fitting about container 10 and removably secured thereto by a plurality of headed screws 71.

A cover 72 is provided for said container, the same being hinged at one side 72a by hinged 45 links 72b and having a curved trough-like portion at its opposite side adapted to fit over a bead 10c formed at the top of container 10. A resilient clasp 73 is arranged to engage the edge of cover 72 to hold it in position. A bail handle 50 74 is disposed substantially centrally of casing 72 having flanged ends secured to said cover by the rivets 75. Handle 74 is apertured so that snap hooks 77 on straps 68 may be engaged therewith. A supplementary handle 76 has semi-cylindrical portions 76a forming finger holds, and is secured to cover 72 between clasp 73 and handle 74 by rivets 76b. A plate 80 extends across container 10 forming a small chamber having a screened bottom 78 secured thereto through which the liquid is poured into said container. A resilient clip bracket 79 is secured to the rear side of container 10 having a semi-cylindrical portion adapted to engage a discharge pipe, and is disposed opposite a bent-in portion 10d of the container 10.

In operation the container 10 is carried on the back of the operator, straps 68 extending over the shoulders of the operator. The front side 10b is next to the operator's back and said back is directly engaged by plate 63. The rear shoulder portions of the operator can enter the depressions 63a and fit therein while depression 63b fits over the back of the operator at a lower position. The liquid to be sprayed is poured into container 75.

10 with cover 12 swung open. Said cover can conveniently be lifted and swung to open position by moving clasp 73 a short distance and lifting the cover with the fingers by engaging supplementary handle 76. The liquid to be sprayed will pass through screen 78 so that no large particles will enter container 10. In the spraying operation the operator holds the spray pipe and nozzle with one hand and oscillates handle 38 with the other. Handle 38 can be disposed in either of the openings 31a in shaft 31 and the discharge conduit 42 can be connected to either of the outlets 41. The handle will be on the side opposite the outlet. The device is thus adapted to right or left handed operators and any operator can change the handle for rest or variation. The oscillation of handle 38 oscillates shaft 31 and diaphragm 28 is reciprocated by member 24. Liquid is drawn through screen 44 which will be 0 of quite fine mesh through the inlet valve 23 and this liquid will be forced upwardly past valve 14 into the chamber of casing 12. Said chamber forms a liquid pressure chamber with air in the top thereof and when the pressure becomes sufficient, liquid will be forced out through the conduit 39 to which conduit 42 is connected. The other outlet 41 will be closed by a suitable plug. As shaft 31 is oscillated rod 60 forming a crank arm is oscillated and the crank arm on rod 53 0 is thus oscillated by link 58. This oscillates shaft 47 so that blades 49 are oscillated in the container and the liquid therein is stirred up and agitated. It will be seen that shaft 47 and plates 49 may be removed by withdrawing key 54 and 5 then removing rod 53 by moving the same outwardly through member 55. The escape of any liquid around rod 39 is prevented by the packing in member 56. Screen 44 can readily be removed by lifting member 45. Said screen can be easily 10 replaced by placing its lower end over plug 23 and then snapping its upper end under projections 45a. The plate 63 provides for ventilation between the same and container 10. The liquid in said container is often cold and the container 15 being of metal is thus also cold and this produces a discomfort when directly against the back of the operator. Plate 63 being spaced from container 10 for most of its width provides for an insulating layer of air between the same and container 10 so that the cold effect of the container is eliminated. The auxiliary handle 76 for lifting the lid is quite useful and convenient.

In Figs. 8 and 9 a modified structure is shown for holding screen 44 in place. Instead of having the screen open at its top and engaged by the clip 45, said screen is closed at its upper end and is held by the arms 82 which are resilient and curved to embrace said screen. Said arms are secured to the casing 12. It will be seen that 15 screen 44 can merely be pushed in between arms 82 to be held firmly in place thereby. Said screen is then easily and quickly removable by merely withdrawing the same from arms 82.

From the above description it will be seen that 15 I have produced a sprayer with some very advantageous features or improvements. The construction is comparatively simple and the parts have been arranged for convenient assembly and efficient operation. The device has been amply demonstrated in actual practice, found to be very successful and efficient and is being commercially made.

This application discloses improvements upon the structure disclosed and claimed in my co-pending application S. N. 157,942, filed August

7, 1937. This application has now matured into Patent No. 2,162,057, granted June 13, 1939.

It will, of course, be understood that various changes may be made in the form, details, arrangement and proportions of the parts, without departing from the scope of applicant's invention, which generally stated, consists in a device capable of carrying out the objects above set forth, in the parts and combinations of parts disclosed and defined in the appended claims. 10

What is claimed is:

1. A sprayer of the knapsack type having in combination, a container of greater width than thickness, a pump cylinder upstanding adjacent the center of said container, an agitator for the liquid in said container having spaced agitating members at either side of said cylinder, a shaft carrying said members and extending horizontally across said container parallel to the long dimension thereof and journalled at the sides 15 thereof and means for actuating said shaft.

2. A sprayer of the knapsack type having in combination, a container of greater width than thickness, a pump cylinder in said container upstanding substantially centrally thereof, a shaft 25 extending horizontally across said container and journalled at the sides thereof extending along the long dimension of said container, spaced blades secured adjacent each end of said shaft at each side of said pump cylinder and extending 30 downwardly therefrom in diverging planes parallel to said shaft and means for oscillating said shaft and blades for agitating the liquid in said container. 35

3. A sprayer of the knapsack type having in combination, a container of greater width than thickness, a pump cylinder upstanding substantially centrally of said container, a shaft extending across the long dimension of said container and journalled at the sides thereof said shaft extending about said cylinder, agitating means within said container carried by said shaft comprising spaced pairs of blades diverging downwardly from said shaft, means for discharging liquid from said container including a second 45 shaft extending parallel to said first mentioned shaft and projecting at one side of said container, the same having means for connection of an operating handle at the outside of said container, an arm secured to said first mentioned shaft 50 outside of said container, a second arm secured to said second shaft between said means and the side of said container and means connecting said arms for oscillating said first mentioned shaft. 55

4. A sprayer having in combination, a container, a pump cylinder disposed centrally in said container, a shaft extending transversely of said container and journalled at the sides thereof, spaced pairs of agitator blades depending from said shaft and disposed respectively at each side 60 of said pump cylinder, the blades of said pairs diverging toward the bottom of said container.

5. A sprayer of the knapsack type having in combination, a container of greater width than thickness, a pump cylinder disposed substantially 65 centrally of said container, a shaft extending across the long dimension of said container and about said pump cylinder, a bearing at one inner side of said container in which one end of said shaft is journalled, agitating means within said 70 container carried by and depending from said shaft, means for discharging liquid from said container including a second shaft extending parallel to said first mentioned shaft and projecting at one side of said container, the same having 75

means for connection of an operating handle at the outside of said container, a second bearing in the opposite side of said container axially aligned with said first mentioned bearing, an 5 arm having a portion journaled in said second bearing, a readily disconnectible coupling connecting said arm and the end of said first mentioned shaft, a second arm secured to said second shaft between said means and the side of said 10 container and means connecting said arms for

oscillating said first mentioned shaft from said second shaft, said last mentioned means being movable with said first mentioned arm away from said container so that when said coupling is disconnected said arm may be moved from said coupling and said first mentioned shaft and agitating means may be removed from said container. 5

HENRY E. BRANDT. 10
